Kenneth Valentine Skipp, London, England

Application June 17, 1949, Serial No. 3,379

Term of patent 14 years

(CL. D44—9)

To all whom it may concern:

Be it known that I, Kenneth Valentine Skipp, a subject of the King of Great Britain, residing at 17 Pembridge Crescent, Notting Hill Gate, London W. 11, England, have invented a new, original, and ornamental Design for a Combined Drinking Cup and Guard Ring, of which the following is a specification, reference being had to the accompanying drawing, forming part thereof.

Figure 1 is a plan view of a combined drinking cup and guard ring, showing my new design;

Figure 2 is a three quarter perspective view from above of the cup; and

Figure 3 is a three quarter perspective view from below of the same cup.

I claim:

The ornamental design for a combined drinking cup and guard ring, as shown.

KENNETH VALENTINE SKIPP.
